J. I. LE BEL

SMOKING PIPE

Filed July 5, 1923

Inventor

J. Isidore LeBel

By William Clinton

Attorney

UNITED STATES PATENT OFFICE.

JOSEPH ISIDORE LE BEL, OF MONTREAL, QUEBEC, CANADA.

SMOKING PIPE.

Application filed July 5, 1923. Serial No. 649,738.

To all whom it may concern:

Be it known that I, JOSEPH I. LE BEL, a subject of the King of Great Britain, residing at Montreal, Province of Quebec, Canada, have invented certain new and useful Improvements in Smoking Pipes; and I do hereby declare that the following is a full, clear, and exact description of the invention, such as will enable others skilled in the art to which it appertains to make and use the same.

The primary object of this invention, which is a smoking pipe, is the provision of means for retaining moisture and nicotine from the tobacco in such a manner that the same cannot be drawn into the mouth through the same. The invention resides in the formation of a moisture chamber in the stem of the pipe, the chamber being formed separate from the passage and in communication therewith through the bowl and through additional ducts.

The chamber contains a piece of absorbent material, for the insertion of which it is necessary that the stem be made in two parts. The connection between the two parts is in the nature of a flat joint which does not become clogged as readily as the usual screw joint.

A further object of the invention is a pipe so constructed that during the operation of smoking, there will be no suction on the nicotine deposited in the bowl.

As a pipe is smoked, the tobacco is converted into a number of elements including smoke and nicotine. An additional feature of the invention lies in the fact that two of these elements, namely smoke and nicotine, are separated in the bowl, and are subsequently prevented from mixing with one another after separation. In this respect, the invention is to be distinguished from other pipes, in which the smoke and nicotine are drawn together into the stem and are supposed to separate on their way to the mouth-piece.

More specifically, the invention makes use of a moisture chamber formed in the stem of the pipe and beneath the draft passage. In order to avoid the entrance of nicotine and moisture into the draft passage, the interior of the bowl is provided with a projection disposed above the draft passage. By this means, the moisture and nicotine avoid said draft passage and are directed downwardly in the direction of the moisture

chamber, the entrance thereof being of such configuration and disposition as to readily receive the moisture and nicotine which is urged downwardly as the burning of the tobacco continues. In this connection it is to be noted that during the burning of the tobacco, the heat generated has the effect of forcing the moisture and nicotine downwardly, so that the tendency of such moisture and nicotine to proceed towards the moisture chamber is positive rather than incidental.

The invention is illustrated in the accompanying drawings, in which:

Figure 1 is a longitudinal section through the pipe;

Figure 2 is a similar view of the mouth-piece;

Figure 3 is a similar view of the bowl and stem;

Figure 4 is a section on the line 4—4 of Figure 1;

Figure 5 is an enlarged detail section of the bowl; and,

Figure 6 is a perspective view thereof, parts being broken away.

Referring to the drawings by reference numerals, the pipe consists of a hollow bowl 1 provided with a stem 2. A draft passage 3 is formed through the stem and communicates with the bowl in the usual manner. A moisture chamber 4 is cut through the stem in substantially parallel relation with the draft passage, and is disposed there-beneath. This chamber also communicates with the bowl. A groove 5 formed in the front wall of the bowl and connecting the inner ends of the draft passage and moisture chamber conducts the nicotine away from the passage and into the chamber. The mouth-piece 6 is connected to the stem by means of an abutment 7 which is threaded for engagement with the forward portion 8 of the moisture chamber. The stem has formed therein the usual passage 9 which communicates with the passage 3 when the stem is turned into its proper position. The joint between the draft passages through the mouth-piece and stem is flat in contrast with the usual threaded joint formed in the corresponding position in other pipes. It is well known that where a screw joint occurs in the draft passage, there is an accumulation of nicotine and other clogging substances. This inconvenience is eliminated by means of the flat joint described above.

100

110

The stem is of substantially triangular cross section with the draft passage passing through a corner. This construction is of light weight and of sufficient strength in spite of the draft passage and moisture chamber formed therein.

A strip of absorbent material 10 is inserted in the abutment 7 and extends into the chamber 4. This material serves to take up the moisture as the latter deposits in the chamber, and can be renewed as often as desired by merely separating the mouth-piece from the same. The chamber 4 may be provided with a tubular lining of glass, aluminum, or similar non-absorbent material, so that the moisture received in this chamber cannot permeate into the wooden walls.

The curvature of the cavity in the bowl is such that there is formed a projection 1' above the inner end of the draft passage 3. As the result of this construction, the nicotine and moisture which are forced downwardly as the burning continues, are simultaneously directed somewhat laterally in order to avoid entering the draft passage. Consequently this material enters the moisture chamber through the opening 5, the latter extending beyond the inner end of the draft passage 3, as a result of which the entrance of the moisture and nicotine into the chamber 4 is greatly facilitated.

In the ordinary use of a pipe, the burning tobacco is changed to ashes, and the moisture and nicotine from such burnt tobacco is forced downwardly into the bowl under the action of the heat produced. Consequently, the moisture concentration of the remaining tobacco increases as the smoking progresses. Finally the concentration of the moisture becomes so great that the tobacco at the bottom of the bowl is saturated with it, and such moisture is then drawn through the stem and mouth-piece. In the present invention, the elements produced in the burning, including the smoke, are separated in such manner that the smoke and moisture follow different paths. In other words, the moisture and nicotine are prevented from entering the draft passage 3 by means of the projection 1', as already pointed out. Under the burning of the tobacco, the moisture and nicotine are forced downwardly into the openings 5, thereafter being absorbed in the chamber 4. The smoke, being lighter than the moisture and nicotine, is attracted by the draft produced in the draft passage, whereupon it is pulled therein. Because of the space between the inner end of the passage 3 and the opening 5, an excessive draft through the smoke passages will not lift the moisture from the chamber 4, especially when the same has been absorbed in the substance 10. It has been found that even an excess of draft through the smoke passages will not raise

the moisture of the moisture chamber. In fact, it is physically impossible to raise such moisture and nicotine after the same have reached a level below the lower wall of the draft passage 3, especially when the nicotine has become absorbed in the material 10.

As an additional feature, a duct 11 is formed in the stem near the inner end thereof and connects the smoke passage 3 with the moisture chamber, as clearly shown in Figures 1 and 3. This duct is inclined forwardly and is supplemented by a similar channel or duct 12 at the forward end of the stem. The functions of the duct 12 are as follows: (1) if the smoke passage becomes clogged at the inner end, the smoke may pass through the channel 11 and to the duct 12, whence it enters the mouth-piece 6; (2) in the normal operation of the pipe, any nicotine or saliva that may be carried into the smoke passage 3 has an opportunity to fall into the moisture chamber through the duct 12 before entering the mouth-piece passage 9; and, (3) the duct 12 permits entrance of nicotine from the intermediate portion of the draft passage into the chamber, because of the vacuum created in the chamber by air drawn through the draft passage.

While a specific embodiment of the invention has been illustrated and described, it is to be understood that various alterations in the details of construction may be made without departing from the spirit of the invention as indicated by the appended claims.

Having thus fully described the invention, what I claim as new and desire to protect by Letters Patent is:—

1. A smoking pipe comprising a bowl and a stem, said stem having formed therein a draft passage and a moisture chamber, both in separate communication with the bowl, said chamber being disposed beneath the passage, and inclined ducts connecting said passage and moisture chamber near the ends thereof.

2. A smoking pipe comprising a bowl and a stem, said stem having formed therein a draft passage and a moisture chamber, both in separate communication with the bowl, said chamber having its entrance opening disposed beyond the inner end of the draft passage in the stem, an inwardly extending projection formed within the bowl and disposed above the draft passage, and inclined ducts connecting said passage and moisture chamber near the ends thereof.

3. A smoking pipe comprising a bowl and a stem, said stem having formed therein a draft passage and a moisture chamber, both in separate communication with the bowl, a mouth-piece having a threaded abutment adapted to be received in said chamber, an

- absorbent substance carried by said abutment and extending into the chamber, the joint between the mouth-piece and stem being flat at the junction of the draft passages therein.
4. A smoking pipe comprising a bowl and a stem, said stem having formed therein a draft passage and a moisture chamber both in communication with the bowl, a mouth-piece having a threaded abutment, a recess formed in one end of said abutment, the other end being solid, and an absorbent substance received in the said recess and adapted to extend into the moisture chamber.
10. A smoking pipe comprising a bowl and a stem of triangular cross section, said stem having a moisture chamber formed therein and a draft passage extending therethrough near a corner thereof, said chamber and passage communicating separately with the bowl, and inclined ducts connecting the chamber and passage near the ends thereof.
15. A smoking pipe comprising a bowl and a stem of triangular cross section, said stem having a moisture chamber formed therein and a draft passage extending therethrough near a corner thereof, said chamber and passage communicating separately with the bowl, and inclined ducts connecting the chamber and passage near the ends thereof.
20. A smoking pipe comprising a bowl and a stem having formed therein a draft passage and a moisture chamber, both communicating separately with the bowl, inclined ducts connecting said passage and moisture chamber near the ends thereof, and a groove formed in the wall of the bowl and connecting the inner ends of the draft passage and moisture chamber.
25. A smoking pipe comprising a bowl and a stem, said stem having formed therein a draft passage and a moisture chamber, both in communication with the bowl, a mouth-piece having a threaded abutment, a recess formed in one end of said abutment, the other end being solid, an absorbent substance received in the said recess and adapted to extend into the moisture chamber, and a groove formed in the inner wall of the bowl and connecting the inner ends of the draft passage and moisture chamber.
30. A smoking pipe comprising a bowl and a stem, said stem having formed therein a draft passage and a moisture chamber, both in communication with the bowl, a mouth-piece having a threaded abutment, a recess formed in one end of said abutment, the other end being solid, an absorbent substance received in the said recess and adapted to extend into the moisture chamber, and a groove formed in the inner wall of the bowl and connecting the inner ends of the draft passage and moisture chamber.
35. A smoking pipe comprising a bowl and a stem, said stem having formed therein a draft passage and a moisture chamber, both in communication with the bowl, a mouth-piece having a threaded abutment, a recess formed in one end of said abutment, the other end being solid, an absorbent substance received in the said recess and adapted to extend into the moisture chamber, and a groove formed in the inner wall of the bowl and connecting the inner ends of the draft passage and moisture chamber.
40. In witness whereof I have hereunto set my hand.

JOSEPH ISIDORE LE BEL.
